UNITED STATES PATENT OFFICE.

JOHN H. BLAKNEY, OF MILWAUKEE, WISCONSIN, ASSIGNOR TO LOURNAY, INC., OF MILWAUKEE, WISCONSIN, A CORPORATION OF DELAWARE.

DESIGN FOR A COLOGNE BOTTLE.

Application filed July 12, 1923. Serial No. 6,770. Term of patent 14 years.

To all whom it may concern:

Be it known that I, JOHN H. BLAKNEY, a citizen of the United States, and resident of Milwaukee, Milwaukee County, Wisconsin, have invented a new, original, and ornamental Design for Cologne Bottles, reference being had to the accompanying drawing, forming part thereof.

In the drawing, Fig. 1 is a front view of the cologne bottle, showing my new design; and Fig. 2 is a vertical central sectional view thereof.

I claim:

The ornamental design for a cologne bottle, as shown.

JOHN H. BLAKNEY.
